FLOYD Y. PARSONS, OF PATERSON, NEW JERSEY.

WALL CONSTRUCTION.

Application filed July 31, 1926. Serial No. 126,130.

This invention relates to building structures and particularly to walls thereof. The principal underlying object is to provide a wall which shall be strong, fire-proof, non-shrinking and adapted to be built at a cost which will not appreciably, if at all, exceed that of building a wall of wood, as the walls of ordinary wooden or frame buildings.

10 In the drawings,

Fig. 1 is a perspective view showing a wall in process of construction according to my invention;

15 Fig. 2 is a side elevation, partly in section, of the wall in process of construction;

Fig. 3 is a horizontal section of a wall built according to the invention, showing the construction with respect to a corner and an opening (as for a window) in the

20 wall;

Fig. 4 is a vertical section on line 4—4, Fig. 2;

Fig. 5 is a horizontal sectional detail illustrating a step in the construction;

25 Fig. 6 is a vertical section on line 6—6, Fig. 1;

Fig. 7 is an elevation showing the construction in the forming of an opening, as for a window;

30 Fig. 8 is a vertical section on line 8—8, Fig. 7;

Fig. 9 is a perspective view of a skeleton system used in accordance with the invention;

35 Fig. 10 shows in end elevation a form structure including such skeleton system; and

40 Figs. 11 and 12 show a template and the manner of using it in the forming of the form structure.

45 Any suitable foundation or foundation wall is first provided. Along this at intervals are placed the form structures which, setting aside for the present certain details relating thereto, it will suffice to say include inside and outside spaced members, the spaces between them being adapted to receive concrete or other suitable plastic material. Between each two adjoining form structures sectional wall elements are placed one upon another, the portion of the ultimate wall formed by these sectional wall elements extending in each instance from one to the other of the form structures in a 50 manner to produce with each of them what

is in effect a mold or form two sides of which are afforded by said members of the form structure and a third side by the said wall portion. In each mold thus produced by the two members of the form structure 60 and the said wall portions (or it may be one such wall portion and a door or window frame or the like) flanking such form structure the plastic material is introduced.

In a wall built up in this way there will 65 result columns of the molded plastic material in alternation with the wall portions composed of the sectional wall elements.

Preferably said wall portions will project into the open sides of the form structures 70 and if the elements forming them are each of a size to reach from one to the other form structure and into each the work can proceed very rapidly and without the exercise

75 of any special skill, the form structures then affording means to determine the positioning of the wall elements and hold them so positioned until the plastic material can be introduced and it sets. The columns formed

80 become vital supporting factors in the completed wall in any event, and it will be noted that if a plastic material having good adhering quality, like concrete, be used there will be a bond between the columns and the

85 portions of the wall formed by the sectional wall elements; further, if each of the said wall elements is of a size to reach from one column to the next there will be no occasion for any bond of the elements directly to

90 each other (as by horizontal layers of mortar between them) because of their described union with or bonding to the columns. Preferably the form structures are

95 constructed in such a way as not only to adapt them to their function in the molding or forming of the columns but to reinforcing the columns; they will also usually be

100 constructed so as to be serviceable for other purposes relating to any means which is applied (inside or outside) in treatment of a naked wall formed as I have outlined.

These form structures also are useful in constructing parts of a wall which reach horizontally, as the plate, across door or window openings, etc. This will serve for a 105 general statement of the invention. As for the details of the invention as herein shown by way of example in connection with the building of a wall of a dwelling:

110 First, as to the form structures: In the

example, each comprises two opposite spaced members 1, preferably wooden strips, arranged in parallel planes and a skeleton system, Fig. 9, tying them together so as to 5 retain them against spreading when the plastic material is introduced between them and preferably including parts which extend lengthwise of said members and in the column that is to be formed constitute the 10 chief reinforcing factors. This skeleton system may be composed of cross-wires 2 arranged at intervals with respect to any number (as two) of longitudinal wires 3 and in some way fixed thereto, as by bending 15 the wires 3 around the cross-wires, the cross-wires having at their ends eyed portions 2^a formed, say, by bending off each end of the cross-wire in a direction perpendicular to the common plane of the wires 2 and 3 and then rebending to form a loop. Suitable 20 lengths of this material may be assembled with the strips 1 as the form structures are required in the following convenient way: A trough-like template 4 having 25 its sides at right angles to each other is provided and on this as shown in Fig. 11 is placed one of the strips 1; then the skeleton system is superimposed upon such strip and nails 5 are driven through its loops 2^a into 30 the strip; and then the partly formed form structure is inverted as shown in Fig. 12 and rested upon the other strip 1 and nailed thereto as in the first instance.

The foundation or foundation wall 6 being laid and the first floor joists 7 of the building being positioned thereon, a strip 8 may be nailed on these joists parallel with outer face of the foundation 6, and upwardly projecting dowels 9 having also been first 35 preferably set in the foundation at suitable intervals, the form structures are stood upright on the foundation in register with or so as to contain the dowels and also so as to abut strip 8 which thus assists in alining them. Other such form structures 10 which are to be used in forming the plate of the wall are then placed horizontally upon the 40 upper form structures as shown in Fig. 2 and they may be held in proper position 45 thereon by the cleats 11. Of course the form structures may be held in position in any way during the assembling thereof: after they have been assembled and the structure they form has been plumbed it 50 may be temporarily braced, as at 12 in Figs. 55 2 and 4.

Wall elements 13 are provided in the form 60 of slabs each of which in the present example is of a horizontal dimension somewhat greater than the distance between two adjoining form structures, or so that in order to assemble any slab in its intended relation to two adjoining form structures it is necessary to enter it endwise between the members 1 of one such form structure and in

skewed position (Fig. 5) and then having brought it into proper alinement with the two form structures shift it endwise sufficiently to leave both ends projecting into the form structures. Sectional wall portions are built up, using these slabs, between each two adjoining form structures as shown in Fig. 1, each stack of slabs or wall elements extending to the level where the plate is to be formed. The result is that forms or 70 spaces are left between the inner and outer members 1 of each upright form structure and the two stacks of slabs which flank the latter, and these several vertical forms or spaces have as a horizontal extension there- 75 of at the top the upwardly open space between the members 1 of the form structure 10 and the top slabs of the several stacks of slabs. Of course the several stacks of the 80 slabs are kept positioned by the ends of the slabs projecting between the members 1 of the upright form structures.

At suitable stages, the concrete or other 85 plastic material is introduced into the several forms or spaces afforded by the upright 90 form structures and the spaced stacks of slabs so as to produce columns of such material between the stacks of slabs and so that when the columns have thus been completed 95 the horizontal space or form for the forming of the plate is filled. The resulting structure, on the setting of the concrete or other 100 plastic material, comprises as a whole, with the foundation or base 6, a series of spaced 105 monolithic columns 14 in Fig. 1, with the stacks of slabs interposed between them, and an integral plate 14^a which is integral or 110 monolithic with the columns; the slabs are united to and in effect integral with the columns because at their ends if concrete or 115 other suitable adhering material is used they become bonded to the columns. The skeleton systems are useful not only in holding the spaced members 1 definitely related to 120 each other (against spreading) at the time the plastic material is introduced but as important reenforcing factors in the ultimate columns, especially with respect to their longitudinal members 3.

After the plate is formed the building of 125 the wall can continue upward in the same manner as before. Where the second story joists 15 rest on the plate a fragment of the corresponding slab may be cut away as shown at 16 in Fig. 1 and the resulting space 130 finally filled with the plastic material as shown at 17 in Fig. 6.

Fig. 3 at the right shows a form structure 18 suitable for use in forming a corner column. Essentially this is the same as the 135 form structure already described except that its spaced members are angular in cross-section, 18^a being its skeleton systems joining such members.

Figs. 7 and 8 illustrate how provision is 140

made for reception in the wall of door or window frames. Where the size of the frame is such that a space would otherwise exist between one or more of its four sides as at top and bottom in these figures, form structures 19 like those already described may be applied and filled in to with the plastic material, as at 20, to provide the necessary fillers. For securing the frame (20^a) in place nails 20^b may be left projecting therefrom so as to become embedded in the concrete columns 14 and the fillers 20 (Figs. 3 and 7).

In the wall completed as so far described the members 1 and 2 will project from the general faces of the walls formed at inside and outside by the flush slabs. Whether these are retained or ripped off later is not material. In the present case, the inside 20 ones will serve as furring for the nailing thereto of the facing material for the inside of the wall, as the lathing 21 carrying the plaster coating 22 (Figs. 3 and 6); the outside ones may serve as means to which an outside facing for the wall may be attached, or they may be removed as shown at the right in Fig. 1 and the whole outer surface then covered with stucco 23, or other finish coat (Figs. 3 and 6).

The integrity of the wall as a whole may of course be increased by any such expedient as that shown in Fig. 5, where the lateral sides or ends of the slabs are channeled at 24, so as to receive the concrete and thereby increase the bond or interlock between the slabs and columns.

Of course, while I have mentioned concrete as the material for forming the columns, the plate, etc., any other cementitious material suitable for the purpose may be employed. In the appended claims I have used the term "piers" in preference to "columns" because of its perhaps more comprehensive meaning.

An advantage of my invention is that, since the columns are the principal load-carrying elements of the wall, the sectional wall portions may not only be formed of relatively thin elements, as slabs, but the material composing such elements may be of an inferior character, as gypsum; if the columns are sufficiently strong, as by being reinforced and properly supported, the integrity of the wall as a whole will be especially complete and permanent when each sectional wall element reaches from one pier to the next, regardless of whether the bonding between the sectional wall portions and each pier is or is not direct in character due to the adhesion of the cementitious material of the piers to said wall portion.

Of course it is not indispensable that the sectional wall elements remain in the wall as permanent constituents thereof; when they have served their purpose in connection with

the forming of the integral skeleton structure that results from the molding and setting of the cementitious material they may, if required in some cases, be removed and they may for this purpose have any form or 70 construction lending itself to their ready removal without disturbing such skeleton structure.

In the example shown and described, where the wall is a wall of a building, the 75 wall and joists 15 may be interlocked as by driving nails or spikes 24 (Fig. 1) laterally into the ends of the joists and so as to project sufficiently to extend into the spaces of the adjacent form structures, so that when 80 the concrete is introduced it will embed such nails or spikes which will then serve as devices tying the joists and wall skeleton together.

I claim:

1. In the constructing of a wall, the herein-described method which consists in first fixing pairs of opposed elongated form members in upright position at intervals from each other along the line of the wall to be constructed and so that said members in each pair are spaced apart and opposed to an upright plane common to the several pairs, then stacking in each interval wall elements, each of a thickness approximately to fit between the members of and each of a length less than the center-to-center distance between the pairs flanking but exceeding the width of such interval, so that each wall element projects into both of the spaces between the members of those pairs which flank such interval and is spaced from each next adjoining stack, and introducing cementitious material into each space formed between adjoining stacks on the one hand 95 and the members of one such pair on the other and thereby forming in such space a pier bonded to such adjoining stacks.

2. In the constructing of a wall, the herein-described method which consists in first fixing pairs of opposed elongated spaced form members, each having a skeleton reinforcement connecting its said members, in upright position at intervals from each other along the line of the wall to be constructed and so that said members in each pair are opposed to an upright plane common to the several pairs, then stacking in each interval wall elements, each of a thickness approximately to fit between the members of and each of a length less than the distance between said re-enforces of the pairs flanking such interval but exceeding the distance between the members of such pairs, so that each wall element projects into both of the spaces between the members of those pairs which flank such interval, and introducing cementitious material into each space formed between adjoining stacks on the one hand 105 and the members of one such pair on the other and thereby forming in such space a pier bonded to such adjoining stacks.

other and thereby forming in such space a pier bonded to such adjoining stacks and containing said re-enforcement.

3. In the constructing of a wall, the herein-described method consisting in placing pairs of upright form members at an interval from each other along the line of the wall to be constructed and so that the members of each pair form a mold space open at a side thereof facing lengthwise of the wall, placing a third pair of form members in traversing relation to the interval between said pairs of form members and so that the members of such third pair form a mold space between them in communication with the first-named mold spaces, placing sectional wall elements in position to close off the first-named mold spaces at their said open sides, and introducing cementitious material into all three mold spaces and thereby forming a pair of piers and an element connecting them all constituting a monolithic structure.

4. In the constructing of a wall, the herein-described method consisting in placing pairs of upright form members at an interval from each other along the line of the wall to be constructed and so that the members of each pair form a mold space open at the side thereof facing the other pair of members, placing a third pair of form members in traversing relation to the interval between said pairs of form members and so that the members of such third pair form a mold space between them open toward said interval and in communication with the first-named mold spaces, placing sectional wall elements in position to close off all three mold spaces at their said open sides, and introducing cementitious material into all three mold spaces and thereby forming a pair of piers and an element connecting them all constituting a monolithic structure.

In testimony whereof I affix my signature.

FLOYD Y. PARSONS.
